CLAIM

The ornamental design for a doorbell, as shown and described.

DESCRIPTION

FIG. 1 is an exploded front, side, and bottom perspective view of a doorbell showing the new design;

FIG. 2 is an exploded back, side, and bottom perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The uniform repeating broken lines depict portions of a doorbell in which the claimed design is embodied and form no part of the claimed design.

1 Claim, 6 Drawing Sheets# US D840,856 S
